UNITED STATES PATENT OFFICE.

MAX KRIEWITZ AND WILLIAM F. FERRIS, OF FAIRFAX, OKLAHOMA; SAID FERRIS
ASSIGNOR TO SAID KRIEWITZ.

CAR-DOOR LOCK.

1,081,755.

Specification of Letters Patent.

Patented Dec. 16, 1913.

Application filed April 28, 1913. Serial No. 764,277.

To all whom it may concern:

Be it known that we, MAX KRIEWITZ and WILLIAM F. FERRIS, citizens of the United States, residing at Fairfax, in the county of Osage, State of Oklahoma, have invented certain new and useful Improvements in Car-Door Locks; and we do hereby declare the following to be a full, clear, and exact description of the invention, such as will enable others skilled in the art to which it appertains to make and use the same.

This invention relates to car door locks, and it more particularly relates to an improved combination lock and seal cutter.

The primary object of this invention is to provide a car door lock by which the door may be more quickly and easily locked and unlocked than is possible when locks of usual construction are employed.

A further object of the invention is to provide a car door lock of this character which is equally applicable and efficacious when applied to either side of the door.

Another object is to provide a lock of this character in which the working elements will not become jammed or bound by the internal pressure against the car door sufficiently to impede the progress of a person in unlocking the door.

A further object is to provide the lock bar with a curved wedge element whereby the hasp of the door is forced to be seated around the staple of the lock.

A further object is to provide a lock of this character by which the door may be locked with the uttermost security.

A further object is to provide a lock of this character which is provided with a shearing device whereby the car seal may be quickly and easily cut by the initial movement of the combined locking and shearing lever.

Another object is to provide a car door lock of this character which is simple of construction, comparatively inexpensive, and thoroughly efficient.

Other objects and advantages may be recited hereinafter in the claim.

In the accompanying drawings, which supplement this specification:—Figure 1 is a fragmental portion of a car having our improved car door lock applied in closed and locked position. Fig. 2 is a view similar to Fig. 1, the lock being in open position. Fig. 3 is a vertical section through the side

wall of a car, showing our improved car door lock in elevation and in locked position. Fig. 4 is a view similar to Fig. 3, except that the lock is in open position, the car seal having been sheared. Fig. 5 is a vertical sectional view through the lock on the line 5—5 of Fig. 1, and Fig. 6 is a transverse section on the line 6—6 of Fig. 1.

Referring to these drawings, in which similar reference characters correspond with similar parts, throughout the several views: The main frame or base plate 10 is secured on the side wall 11 of a car by means of bolts 12, or other proper securing means, and this base plate is formed of tough and strong sheet metal, being preferably stamped from sheet steel and has apertured ears 13 struck up therefrom. These ears are each provided with an inclined slot 14, these slots being disposed opposite to each other and adapted to have an ordinary seal strip 15 passed therethrough. The upper end of the plate 10 is provided with a tongue 16 which is formed with a semi-cylindrical boss 17 and an opposite groove 18. In a plane above the ears 13 below the boss 17 is a staple 19, which may be secured to the plate 10 by any proper means or in any proper way, but we prefer that the staple shall be welded fast to the plate 10 or formed integrally therewith, so as to obtain the maximum strength and security. The usual or any preferred form of hasp 20 is adapted to be seated over the staple 19, and when such hasp is secured to the car door it will be seen that the staple coacts therewith for preventing the door from sliding and opening. A combined locking and shearing bolt or lever 21 is formed with a handle 22 which may be of any desired formation, and the opposite end of the member 21 is tapered or wedge-shaped, being also curved or of semi-crescent formation as illustrated at 23. With the exception of the handle and the semi-crescent element, the member 21 is preferably quadrangular in cross section, and is provided with a widened portion 24, having an inclined slot 25 therethrough.

The outer surface 26 of the semi-crescent bolt element is preferably convexed at right angles to the concavity which forms the inner curve of the semi-crescent bolt element, so as to conform to the inner surface of the staple 19, while the cutter element 27 which is normally disposed between the ears 110

13, is not only quadrangular in cross section, but its outer edges are sharp and relatively hard, and may be either case hardened or tempered, and may be formed either integrally with or secured to the lever or bar 21. The ears 13 have their upper portions, above the slots 14, either tempered or otherwise hardened; so that the edges which outline these slots constitute cutting edges. A 10 limiting and securing member or link 28 is formed from a length of wire, preferably of springy material, and is curved at its medial portion to form a loop 29, while its end portions are bent outward at 30, lying 15 parallel at 31 and extending inward toward each other at 32, while the portions of the link between the loop 29 and the shoulders or fulcrums 30 lie substantially parallel with each other and are spaced apart sufficiently to receive the staple 19 therebetween. 20 The inturned ends 32 are seated within the groove 18, while the fulcrums 30 rest against the plate 10. It will be seen that the elements 31 lie in a different plane from the 25 elements 28, so that the latter are inclined to the plane of the plate 10. The loop 29 engages with the slot 25, and the semi-crescent bolt element extends normally through the staple 19 and bears against the 30 hasp 20, so as to hold it in engagement with said staple, while the cutter element 27 fits snugly between the ears 13 and is held normally between said ears by means of the seal or strip 15. The outward pressure of 35 the loop 29, caused by the spring action of the link, holds said loop in the lower and outer end of the slot 25, so as to retain the bolt element 23 in its upper position, so as to exert a continual wedge action against 40 the hasp for holding it toward the plate 10. However, when it is desired to unfasten the door, this wedge action is relieved when the member 21 is pulled downward.

In operation, the operator grasps the 45 handle 22, and pulls downward and outward simultaneously, so that the cutter element 27 not only presses against the sealing strip 15, but also slides thereagainst, so that the shearing action is similar to that of other 50 cutting machines or devices, such, for in-

stance, as a paper cutting machine, in which a pressure and a longitudinal movement of the knife is essential for producing the most efficient operation. Now, assuming that the door is open and is to be closed, and locked, and assuming that the relation of the car door and lock are such, as is often the case, that the hasp binds upon the staple, or is sprung outward, so that it is difficult to seat it over the staple. In such event, the pointed 60 end of the semi-crescent bolt element is inserted between the hasp and staple, and in forcing this semi-crescent or wedge element through the staple, the hasp is forced into its proper position, and the spring link 28 and sealing strip 15 hold the member 21 in its locking position.

From the foregoing, it will be seen that we have provided a car door lock of this character which is fully capable of attaining the foregoing objects in a thoroughly practical and efficient manner.

We do not limit our invention to the exact details of construction, combination and arrangement of parts, as herewith illustrated and described, but our invention may only be limited by a reasonable interpretation of the claim.

We claim:—

A car door lock consisting of a staple 80 adapted to engage with a hasp, a slotted locking member having a wedge-shaped end portion extending through the staple and securing the hasp thereon, means coacting with a sealing element for retaining the 85 member in engagement with the staple, and a link extending through the slot of said member for allowing it to move longitudinally so as to disengage it from the sealing element and to simultaneously disengage it 90 from the staple, said link being adapted to support said member when in its inoperative position.

In testimony whereof, we affix our signatures in the presence of two witnesses.

MAX KRIEWITZ.
WILLIAM F. FERRIS.
